(57) **CLAIM**

We claim the ornamental design for a model vehicle wheelie bar assembly, as shown and described.

DESCRIPTION

FIG. 1 is an upper, left, front perspective view of a model vehicle wheelie bar assembly showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is an upper plan view thereof;

FIG. 7 is a lower plan view thereof; and,

FIG. 8 is a lower, right, rear perspective view of the model vehicle wheelie bar assembly.

The broken lines in the drawings illustrate portions of the model vehicle wheelie bar assembly that form no part of the claimed design.
